PIER CONNECTION

Nathan Chayes, New Rochelle, and Richard Blum, Purchase, N. Y., assignors to Chayes Dental Instrument Corporation, New York, N. Y., a corporation of New York

Application November 3, 1933, Serial No. 696,494

1 Claim. (Cl. 32—5)

This invention relates to removable dentures and particularly to that class of such devices in which the denture is removably held in place by substantially T-shaped parts on one member fitting into sockets in the other members shaped to receive the T-shaped members. To provide a yielding interlock between these parts, it has been the practice to split the head members in various ways with a view to forming spring tongue members. The metal of the head however is not well suited to this additional spring function, the tongues quickly losing their resiliency, breaking off, or failing in other respects.

Special objects of this invention are to provide simple and practical means for holding the denture in which the above mentioned faults are eliminated; in which the desired holding tension may be provided, in which the holding tension will be of a lasting or more permanent character and of such nature that it may be removed in case of breakage or the like.

The foregoing and other desirable objects are attained in this invention by certain novel features of construction, combinations and relation 25 of parts, as set forth in the following specification.

In the accompanying drawing forming a part of this specification, the invention is illustrated in the preferred form but it should be understood that the structure is capable of modification without departure from the broad spirit and scope of the invention as hereinafter defined and claimed.

Fig. 1 is a perspective view illustrating the invention as applied to and in use for removable bridge work.

Fig. 2 is an enlarged perspective view of the head member of the denture as constructed with a resilient or holding element seated in a proper slot in the face of the same.

Fig. 3 is a similar view of the socket designed to receive the head.

Fig. 4 is a plan view of an assembly of head and socket.

Fig. 5 is a section taken substantially on the line 5—5 of Fig. 4; and

Fig. 6 is a perspective view of a tension member used in the invention.

Referring now to the drawing, 10 indicates generally the head member, which as shown, is 50 of generally T-shaped form made up of a neck portion 11 and a cross-head portion 12. This cross-head portion 12 is provided with a wide slot extending from top to bottom and having walls 14 and 15. These walls 14 and 15 are provided with dovetail grooves 16. The neck portion

11 is provided with a recess 17 at the lower extremity thereof and adjacent the cross-head 12 for a purpose to be explained later.

The socket member is indicated generally at 20, being in the form of a shell having a cavity to receive the cross-head T-shaped member and having a wide slot 21 for the neck portion of the head member. This slot 21 does not extend the full length of the socket 20 as shown. The wall portion 22, the long front wall and the bottom part 24 form a snug seat for the lower part of the cross-head 12. The upright walls of the recess 21 are reenforced as at 25 to aid in retaining the cross-head within the socket.

In order that the cross-head may be removably held in the socket, use is made of spring members A of the character shown in detail in Fig. 6. Each spring member is made from flat stock and is formed into substantial U-shape with one portion 30 and a second portion 31. The portion 30 has its longitudinal edges tapered as at 32 to fit in the dovetail slots 16 in the cross-head. The portion 31 is of width slightly less than the distance between the walls 14 and 15 so that this part 31 can lie between these walls with its outer surface in substantial alignment with the outer surfaces of the cross-head. The material used for the spring is preferably a corrosive resisting steel alloy which is not affected by mouth or food acids and which is very tough and ductile. This material has very good elastic properties whereby an efficient spring can be made therefrom.

The application and use of the elements of the present invention are substantially as follows: Sockets 21 are properly positioned and secured in pier teeth 49, while head members 10 are secured to a removable denture in the nature of teeth 41. After the sockets and the head members have been properly secured in place, spring members A are seated in the slots in the faces of the cross-heads 12 of the cross-head members 10. In other words, these springs are not inserted until all heating operations, such as soldering, casting, or spot-welding, have been completed. The springs are inserted from the lower ends of the cross-heads 12 with the tapered edges 32 of the expanses 30 fitting in the dovetail slots 16. When properly inserted, the upper edge of each expander 30 will be in substantial alignment with the top of a head member 10. In this seated position the expanses 31 extend outwardly somewhat from the faces of the cross-heads 12, but the expanses 31 can be pressed into the spaces between the walls 14 and 15 of the slots in the cross-heads.

The removable denture is now in condition to

be inserted in its place, which insertion is accomplished by pressing the cross-heads 12 into the sockets 21. Such insertion causes the expanses 31 of the springs A to be compressed into the 5 slots in the cross-heads, but due to the resiliency of these springs the expanses will be forced against the long front walls of each socket. When properly seated in the sockets, it will be observed by reference to Figure 5 that the lower 10 end of each cross-head fits into the seat provided by the bottom 24, the front wall and the short rear wall 22, provision for such seating being made by the recess 17 in the neck portion 10.

With this arrangement a good connection between 15 the removable denture and the pier teeth is secured. It is well-known that a natural tooth is set in the jawbone in a cushioned socket, more or less tapered, and that the tooth actually moves when in use. Hence, it is necessary that the attachment 20 between the removable denture and the pier teeth be capable of a slight movement, but at the same time be held firmly in position with just the right amount of tension, so that the patient may remove the denture and replace the 25 same at will. If after repeated removal and replacement of the denture the springs lose some of their tension to hold the denture in place properly, the tension can be renewed by simply forcing the expanses 31 outwardly from the expanses 30 a slight amount. Due to the material 30 used in the spring this renewal of tension can be accomplished many times without destroying the resiliency of the springs. However, if one of the spring members should become broken due to 35 repeated use, it can be renewed or replaced very easily by simply removing the taper-edged ex-

panses 30 and inserting a new V-shaped spring member in the place of the broken member.

This new type of connection assures a better fit between the head of the removable denture and the socket due to the fact that practically the entire outer surfaces of the expanses 31 of each spring member are in contact with the front walls of the sockets. At the same time the very slight movement essential to the connection when the denture is in actual use is provided.

From the foregoing it will be seen that the present invention provides a new, simple, efficient and readily replaceable tension member for removable dentures, which connection and tension member overcomes the faults inherent in previous structures. While the preferred form of the invention has been illustrated, it will be apparent that modifications can be made therein, in view of which any limitations imposed upon the invention are to be only such as are set forth 10 in the following claim.

We claim:

In removable dentures a substantially T-shaped head member and a co-acting socket member, the face of said head member being provided with a 25 slot extending the full length thereof, the walls of said slot being provided with undercut grooves, a substantially V-shaped head member capable of being folded to lie with the expanses thereof in substantially flat contact, one expande of said 30 retaining member being shaped to fit in said grooves and the other expande being shaped to lie between the walls of said slot and to substantially fill said slot when the expanses are forced together.
